LOCOMOTIVE DRIVING BOX

Russell H. Campion, Milwaukee, Wis., assignor of seven-eighths to Eugene E. Campion, Milwaukee, Wis.

Application December 31, 1937, Serial No. 182,811

2 Claims. (Cl. 308—66)

This invention pertains to locomotive driving boxes, and more particularly to wedge bolts utilized in connection with the same, for automatically compensating for wear between surfaces of the driving box, and the shoes and wedges.

At the present time it is common practice to construct wedge bolts for the foregoing purpose, in one piece, with the result that upon stripping of the bolt threads, or breakage of the bolt or take-up spring, an annoying maintenance problem is encountered, in that it becomes necessary to remove the heavy pedestal binder in order to replace the damaged or broken parts. This operation requires several men, and a considerable period of time.

It is, therefore, the primary object of the present invention to provide a wedge bolt, which permits repair or replacement of broken or damaged parts without removal of the wedge or pedestal binder.

Incidental to the foregoing, a more specific object of the invention resides in the provision of a sectional wedge bolt, in which the threaded shank is detachably connected to the bolt head engaged in the wedge.

With the above and other objects in view, which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing:

Figure 1 is a fragmentary elevation of a conventional locomotive frame and driving box, with one form of the present invention applied thereto.

Figure 2 is an enlarged detail section taken on the line 2—2 of Figure 1.

Figure 3 is an elevation of a bolt constructed in accordance with the invention, the section being spaced apart; and

Figure 4 is an elevation of the bolt in assembled position.

Referring now more particularly to the accompanying drawing, the numeral 1 designates one of the side frames of a locomotive bed, the same being provided with the usual pedestal 2 con-

sisting of spaced, depending jaws 3 and 4, respectively, the latter being tapered on its inner face for the purpose hereinafter explained.

Positioned within the pedestal is a driving box 5 for reception of the driving axle 6 of the locomotive. Secured to the bottom of the frame 1, below the pedestal, is a binder 7, which serves to lock the driving box 5 in the frame. Disposed between the driving box 5 and the tapered pedestal jaw 4 is a wedge 8, the lower end of which is provided with a transverse, dove-tailed groove 9, for reception of a wedge bolt 10.

The structure thus far described is more or less conventional, and forms no part of the present invention other than in the combination hereinafter claimed. The salient feature of the invention consists in the novel construction of the wedge bolt 10, which, as shown in the drawing, comprises a head 11 for insertion into the dove-tailed groove 9 of the wedge 8. Detachably connected to the head 11 is a threaded shank 12, which projects loosely through the pedestal binder 7. The lower end of the shank also passes loosely through a depending spaced horizontal tail 13, carried by the binder, and terminates in a nib 13 for reception of a wrench, or other suitable tool, for manipulating the shank. The upper end of the shank is provided with a reduced threaded extension 14, which is screwed into a socket formed in the head 11.

In assembling the shank and head a lock washer 15 is preferably disposed between the two to prevent their detachment through vibration.

Positioned upon the wedge bolt 10, between the binder 7 and tail-piece 13, is a floating plate 16, provided with fingers 16' adapted to straddle the tail-piece to prevent rotation of the plate on the bolt. Disposed between the plate 16 and the tail-piece 13 is a take-up spring 17, which normally urges the bolt upwardly to force the wedge 8 into operative position between the driving box 5 and the pedestal jaw 4, thus automatically compensating for wear between the parts. An adjusting nut 18, threaded on the shank 12 above the plate 16, serves to regulate the tension of the take-up spring 17.

From the foregoing explanation, considered in connection with the accompanying drawing, it is believed that the operation of the invention will be apparent, in that upon stripping of the threads on the shank 12, or breakage of the shank or take-up spring 17, it is unnecessary to remove the binder 7 in order to replace the bolt, or take-up spring, as heretofore required in the use of one-

piece wedge bolts. Instead, the shank 12 can be readily disconnected from the head 11 with any suitable tool, and a new shank or take-up spring inserted for replacement.

5 Thus, it will be seen that an exceedingly awkward and tedious operation is eliminated, it being borne in mind that the average pedestal binder weighs approximately four hundred pounds, and, therefore, requires the assistance of several workmen to handle the same, and remove the several bolts employed for its attachment.

I claim:

1. The combination of a pedestal, a driving box carried by the pedestal, a wedge disposed between the driving box and pedestal jaw and provided with a horizontal dove-tailed groove, a binder secured to the lower end of the pedestal beneath the wedge, a wedge bolt including a head positioned in said wedge groove and a threaded

shank loosely passing through said binder and detachably connected to said head, and a spring disposed between said binder and wedge bolt below the binder to urge the wedge into operative position.

2. The combination of a pedestal, a driving box carried by the pedestal, a wedge disposed between the driving box and pedestal jaw and provided with a horizontal dove-tailed groove, a binder secured to the lower end of the pedestal beneath the wedge and provided with a spaced tail, a wedge bolt including a head positioned in said wedge groove and a detachable, threaded shank loosely passing through said binder and tail, a take-up spring mounted on said shank between 10 said binder and tail, and means on the shank for regulating the tension of said spring.

RUSSELL H. CAMPION.
